UNITED STATES PATENT OFFICE.

CHARLES R. LENTZ, OF INDIANAPOLIS, INDIANA, ASSIGNOR OF ONE-HALF TO JOHN H. SHOAF, OF INDIANAPOLIS, INDIANA.

MACHINE FOR MECHANICALLY CLEANING CRACKER AND CAKE CUTTERS.

1,053,954.

Specification of Letters Patent. Patented Feb. 18, 1913.

Application filed April 9, 1912. Serial No. 689,554.

To all whom it may concern:

Be it known that I, CHARLES R. LENTZ, a citizen of the United States, residing at Indianapolis, in the county of Marion and State of Indiana, have invented certain new and useful Improvements in Machines for Mechanically Cleaning Cracker and Cake Cutters, of which the following is a specification.

10 This invention relates to a machine for mechanically cleaning cutters used in connection with cracker, cake and like machines; and the object of the invention consists in the provision of a machine of the 15 above character wherein cutters above noted, which are heavy and clumsy, may be expeditiously, economically and effectively cleaned.

I accomplish the above object of the invention by means of a machine illustrated 20 in the accompanying drawings, forming a part hereof, in which—

Figure 1 is a vertical section through the machine, on the dotted line 1—1 in Fig. 3, showing the cutter-head in position to be 25 washed and cleaned. Fig. 2 is a side elevation of the machine with the drive pulleys omitted. Fig. 3 is a longitudinal section through the machine on the line 3—3 in Fig. 1. Fig. 4 is a fragmentary detail view 30 showing the locking device in an unlocked position. Fig. 5 is a fragmentary detail plan view on the line 6—6 in Fig. 1. Fig. 6 is a fragmentary detail plan view on the line 6—6 in Fig. 1. Fig. 7 is a detail 35 sectional view of the lower end of one of the cutters showing the recess or cup formed therein.

In the drawings, 10 represents the main body of the machine which acts as a reservoir 40 for retaining the water in which the cutters are washed and cleaned. This body is supported on suitable legs 11. The body 10 is extended vertically for some distance by means of a hood 12 which is bolted fast 45 to the upper edge of the body 10. Arranged vertically within and near each end of the hood 12 is a shaft 14, and these shafts reciprocate through apertures formed in the horizontally disposed ears 15 formed integrally on the standard 16, the latter being carried by and secured to the top of the 50 hood 12. The lower ends of the shafts 14, which project into the chamber formed by the walls of the body 10 and the hood 12

are tied together by means of a cross-beam 55 17, from which the cutter-head 18 is suspended. The slots 24^a permit the bolts 24 to be moved toward or away from each other in order to accommodate cutter-heads of different widths. The cutter-head 18 is of 60 the usual form, and is provided on its lower surface with the cups or cutters 19, and at each end with the arches 20. The arches 20 are provided with transverse slots 21 which communicate with the larger slots which 65 engage the slots 21 and 22.

Cracker and cake machines are provided with bolts to hold the cutter-heads in operative position. The slots 21 and 22 are taken advantage of in the present machine to suspend the cutter-head 18 from the cross-beam 17, and is accomplished by means of suitable bolts 24, which extend vertically through longitudinal slots 24^a in the cross-beam 17, the bolt-heads on the lower ends of the bolts 70 24 entering the slots 22 when the cutter-head 18 is moved laterally into position under the cross-beam 17.

As the cutter-head is quite heavy, easily 80 requiring the services of two persons, I provide means for temporarily supporting said cutter-head from the cross-beam 17. This is accomplished by providing a support 25, shown by means of dotted lines in Fig. 3, said support resting on the upper edge of 85 the body 10, and the forward end being held by the bracket 26, secured to the wall of the body 10.

To enable the cutter-heads 18 to be moved 90 into and out of the machine requires a portion 30 of the side wall of the hood 12 to be made removable, as shown in Fig. 3 of the drawings, and said side member is retained in position by means of a spring-catch 31 arranged at each end of the machine. A piece 95 of felt packing 32 may be interposed around the edge of the removable portion 30 of the side wall and the adjacent edges of the walls of the hood 12, to prevent the escape of water when the machine is in operation.

As before stated, the cutter-head 18 is supported from the cross-beam 17, secured to the lower ends of the vertical shafts 14. In order to move the cutter-head into and out of the water within the body 10, I impart 105 a reciprocating movement to said shafts 14 and cross-beam 17. This reciprocating movement is secured by means of connect-

ing-rods 35, one of which is arranged alongside each end of the machine. The upper ends of these rods pivotally engage the blocks 36, which are made fast to the shafts 5 14, and the lower ends of said heads have an eccentric connection with the pinions 37 mounted on the shaft 38. A connecting-rod 35 engaging each shaft 14 insures a uniform application of power to the reciprocating 10 parts and prevents binding. The pinions 37 are driven from smaller pinions 39 arranged on the shaft 40, and by means of the pulleys 43, which carry a belt 44, leading to a suitable power source, the machine is driven. 15 Each cutter-head 18 is provided, in the usual way, with a number of cutters or cups 19 which cut the crackers and cakes from the dough, and these cups are recessed in their lower ends, as shown in Fig. 7 of the drawings, to provide a cutting edge to cleanly 20 cut the crackers and cakes from the dough. These recesses in the lower ends of the cups become clogged with dough and to keep the cutter-head in a sanitary condition requires 25 frequent washing.

To effectively and mechanically clean the outside and inside of the cups 19, I arrange upon the bottom of the body 10 a brush 45, the bristles of which project vertically into 30 the path of travel of the cups.

As each cutter-head is provided with a yieldable plate 46, which prevents the dough from being lifted off of the table when the cups are withdrawn, I provide means for forcing 35 said plate upwardly on the downward travel of the cutter-head 18, so that the lower exterior surfaces of the cups will be free of obstruction and easy to clean. This is accomplished by securing to the bottom of the 40 body 10, and at opposite ends of the brush, an L-shaped-member 50. The height of these members is such that the plate 46 will be forced upwardly away from the ends of the cups when the cutter-head 18 reaches the 45 limit of its downward stroke. As the bristles of the brush are of a length equal to the height of the members 50, it will be seen that as the ends of the cups emerge from the plate 46, they immediately engage the 50 bristles of the brush, so that the dough will

be thoroughly scrubbed off while the head 18 is reciprocated.

Having thus fully described my said invention, what I desire to secure by Letters Patent, is—

55

1. A washing machine for cleaning cutter heads comprising a body adapted to form a water-holding reservoir, a pair of vertically disposed shafts arranged in said reservoir, guide-ways for said shafts, means for connecting said shafts and for supporting the cutter-head, a brush arranged on the bottom of the reservoir and adapted to clean the cutting faces of the cutter-cups, and means for imparting reciprocating movement to said shafts and cutter-head to move the latter into contact with said brush. 60

2. The combination with an adjustable supporting means for supporting a cutter-head, a water-holding reservoir for submerging said cutter-head, a brush arranged on the bottom of the reservoir and adapted to clean the cutting faces of the cutter-cups, and means for imparting reciprocating travel to the cutter head supporting means 70 to move the cutting faces of the cutter-cups into and out of contact of said brush. 75

3. The combination with a supporting means for supporting a cutter-head and yieldable dough removing plate, means for 80 adjustably connecting said cutter-head on said supporting means, a water-holding reservoir within which to submerge said cutter-head, a brush for contacting the face of said cutter-head when the latter is lowered, 85 means arranged within the bottom of the reservoir to contact and force the yieldable plate away from the ends of the cutter-cups, and means for imparting reciprocating travel to move said cutter-head into and out 90 of contact of said brush.

In witness whereof I have hereunto set my hand and seal at Indianapolis, Indiana, this 20th day of March, A. D. one thousand nine hundred and twelve.

CHARLES R. LENTZ. [L. S.]
